UNITED STATES PATENT OFFICE.

FRANCIS I. DU PONT, OF WILMINGTON, DELAWARE.

EXPLOSIVE PROJECTILE.

1,015,943.

Specification of Letters Patent.

Patented Jan. 30, 1912.

Application filed May 29, 1911. Serial No. 630,009.

To all whom it may concern:

Be it known that I, FRANCIS I. DU PONT, a citizen of the United States, residing at Wilmington, county of Newcastle, and State of Delaware, have invented a new and useful Improvement in Explosive Projectiles, of which the following is a full, clear, and exact description, reference being had to the accompanying drawings, which form a part 10 of this specification.

The object of my invention is to provide means for exploding a projectile, for instance a shrapnel shell, as soon as it has traveled a given distance from the gun.

15 In a patent issued to me June 20, 1911, No. 995,635, I have set forth and claimed a projectile embodying a fly-wheel within the shell and rotatable on its longitudinal axis, and primer-exploding means, rotatable with 20 the shell and geared to the fly-wheel, arranged to function after a pre-determined number of revolutions of the projectile around the fly-wheel. The number of revolutions that the projectile will make in traveling a given distance is a known factor; and by adjusting the gearing so that the parts will function after such number of revolutions, the firing mechanism will operate after traveling such given distance.

25 The object of the present invention is identical, in a broad sense, with that of said patent and embodies the broad invention thereof; but specifically the object of my invention is to improve and simplify the primer-exploding means and enlarge the range of adjustment.

Figure 1 is a longitudinal section of a projectile embodying my invention. Fig. 2 is a cross section on line 2—2, Fig. 1. Fig. 3 is an enlarged detail view of the sliding nut. Fig. 4 shows the firing disk in enlarged views.

30 α is a shell with the space β to be filled with explosives.

35 ϵ is a tube or casing the forward end of which extends into a recess d in the point of the shell and the rearward end of which has an annular flange e , the rim of which abuts against an annular shoulder f formed 40 on the inner wall of the shell.

45 g is a cap screwed into the base of the shell and clamping the flange e against the shoulder f .

50 h is a fly-wheel located within the space formed between the cap g and flange e and

freely rotatable on ball bearings engaging the cap and flange respectively.

i is a screw secured to and rotatable with the fly-wheel. The screw i extends through the tube c and its forward extremity rotates 30 within a recess j formed in the base of the recess d . The axis of the fly-wheel h and screw i is coincident with the longitudinal center of the projectile.

k is a nut on the screw i . The nut k has 35 projections l which extend into longitudinal grooves m formed in the inner wall of the tube c and is thereby prevented from turning relatively to the shell.

n is a disk securely fastened to the forward end of the screw i .

The nut k carries on its front face some friction material o , such as match head composition. The rear face of the disk n is roughened, as by radial grooves p .

q , r , is a series of holes formed in the forward end of the tube c and through which the fire is communicated to the explosive material in the space b .

Previous to firing the projectile, the nut k is positioned on the screw at a point determined by the desired distance from the muzzle of the gun at which the bursting is to take place. When the projectile starts its flight, the nut k rotates with the shell, but 45 the fly-wheel h and screw i do not get started by the force that determines the rotation of the shell, and therefore remain stationary, nearly so. Hence, as soon as the projectile starts to rotate, the nut k starts to move toward the point of the projectile. After a certain number of revolutions, the primed face of the nut k contacts with the roughened face of the disk n . This occurs a time when the projectile is rotating at a 50 high velocity and the fly-wheel and screw are substantially not rotating. The result will be that the primed face of the nut k will slide upon the roughened surface of the disk n and ignite the priming material p . 55 The fire will flash through the holes r and ignite the explosives in the space b .

The invention is not limited to the specific mechanism described and shown nor to the particular means set forth for producing 60 fire. For instance, two materials which produce fire could be used such as red phosphorus and a potassium chlorate and combustible matter mixture, and the red phosphorus could be carried by one of the mem- 65

bers k or n and the chlorate mixture by the other member, so that fire would be produced when the two members came into sliding contact. As another example, one of the members k or n may be made of hard steel and the other member may carry flint.

Having now fully described my invention, what I claim and desire to protect by Letters Patent is:

10 1. In a projectile, the combination with the shell, of mechanism positioned wholly within the shell and rotatably mounted in bearings therein on an axis coincident with the longitudinal center line of the shell, 15 other mechanism rotatable with the shell and gearing with the first named mechanism, and firing means carried by each of said mechanisms, arranged to function with each other after a pre-determined number 20 of revolutions of the shell around the first named mechanism.

2. In a projectile, the combination with the shell, of a fly-wheel located within the shell and rotatably mounted in bearings 25 therein on the shell's longitudinal axis, members, geared together, partaking respectively of the relative movements of shell and fly-wheel, and priming means carried by said members and adapted to function only 30 after a predetermined number of revolutions of the shell around the fly-wheel.

3. In a projectile, the combination with the shell, of a fly-wheel located within the shell and rotatably mounted in bearings 35 therein on the shell's longitudinal axis, members geared together and partaking respectively of the relative movements of shell and fly-wheel, said members including opposing priming faces adapted to slidably 40 contact after a pre-determined number of revolutions of the shell around the fly-wheel.

4. In a projectile, the combination with the shell, of a fly-wheel and screw located within the shell and freely revoluble relatively 45 thereto on the shell's longitudinal axis, a nut on the screw movable longitudinally thereof, and priming means carried by said nut and screw respectively and adapted to function after a pre-determined longitudinal 50 movement of the nut along the screw.

5. In a projectile, the combination with the shell, of a fly-wheel and screw located within the shell and freely revoluble relatively thereto on the shell's longitudinal axis, a nut on the screw movable longitudinally thereof, priming material, and means on the screw adapted to arrest said nut and ignite said priming material. 55

6. In a projectile, the combination with the shell, of a fly-wheel and screw located 60 within the shell and freely revoluble relatively thereto on the shell's longitudinal axis, a nut on the screw movable longitudinally thereof, a disk on the screw, and priming means, on opposite faces of the nut and 65 disk, adapted to be ignited when the nut in its longitudinal movement contacts with the disk.

7. In a projectile, the combination with the shell, of a fly-wheel and screw located 70 within the shell and freely revoluble relatively to the shell on the latter's longitudinal axis, a tube secured to the shell and through which the screw extends, a nut on the screw movable in longitudinal guides on 75 the tube, a disk on the screw, and priming means on opposing faces of the nut and disk, said tube being orificed adjacent to the disk to permit the fire from the primer to flash 80 into the space within the shell surrounding the tube.

8. In a projectile, the combination with the shell, of a fly-wheel located in the base of the shell and freely revoluble relatively thereto on the longitudinal axis of the shell, 85 a screw secured to the fly-wheel and revoluble on the same axis and extending from the fly-wheel to the point of the projectile, a nut on the screw and movable longitudinally thereof, and priming means operable 90 by the nut after a pre-determined movement of the same along the screw.

In testimony of which invention, I have hereunto set my hand, at Philadelphia, on this 24th day of May, 1911.

FRANCIS I. DU PONT.
